(57) **CLAIM**

The ornamental design for a photographic type portable flash, as shown and described.

DESCRIPTION

FIG. 1 and FIG. 2 are perspective views of the photographic type portable flash of the new design, consisting of a body and a flash head.

FIG. 3 is a front view of the flash head of the photographic type portable flash of the new design, shown separately to reveal aspects of the design that may not be apparent in the other views;

FIG. 4 is a rear view of the flash head of the photographic type portable flash of the new design;

FIG. 5 is a left view of the flash head of the photographic type portable flash of the new design;

FIG. 6 is a right view of the flash head of the photographic type portable flash of the new design;

FIG. 7 is a top view of the flash head of the photographic type portable flash of the new design;

FIG. 8 is a bottom view of the flash head of the photographic type portable flash of the new design;

FIG. 9 and FIG. 10 are perspective views of the flash head of the photographic type portable flash.

FIG. 11 is a front view of the body of the photographic type portable flash of the new design, shown separately to reveal aspects of the design that may not be apparent in the other views;

FIG. 12 is a rear view of the body of the photographic type portable flash of the new design;

FIG. 13 is a left view of the body of the photographic type portable flash of the new design;

FIG. 14 is a right view of the body of the photographic type portable flash of the new design;

FIG. 15 is a top view of the body of the photographic type portable flash of the new design;

FIG. 16 is a bottom view of the body of the photographic type portable flash of the new design; and,

FIG. 17 and FIG. 18 are perspective views of the body of the photographic type portable flash.

(Continued)

The broken lines shown in the drawings depict portions of the photographic type portable flash that form no part of the claimed design.
